(57) **CLAIM**

I claim the ornamental design for a clothes hanger cover, as shown and described.

DESCRIPTION

FIG. 1 is a perspective view of a clothes hanger cover, showing my new design in a closed configuration;

FIG. 2 is a perspective view thereof, illustrated in an open configuration;

FIG. 3 is a front elevational view of FIG. 1, the rear elevational view being a mirror image thereof;

FIG. 4 is a left-side elevational view of FIG. 1, the right-side elevational view being a mirror image thereof;

FIG. 5 is a top plan view of FIG. 1;

FIG. 6 is a bottom plan view of FIG. 1; and,

FIG. 7 is a cross-sectional view thereof, taken along lines 7-7 of FIG. 4. The opposite side of the cross-section is a mirror image.

The broken lines showing a hanger in FIG. 1 and items in pockets in FIG. 2 depict environmental matter and form no part of the claimed design.
